UNITED STATES PATENT OFFICE.

FRANCIS F. BROWNE, OF HYDE PARK, ILLINOIS.

SASH-FASTENER.

SPECIFICATION forming part of Letters Patent No. 345,273, dated July 13, 1886.

Application filed July 30, 1885. Serial No. 173,109. (No model.)

To all whom it may concern:

Be it known that I, FRANCIS F. BROWNE, of Hyde Park, in the county of Cook and State of Illinois, have invented certain new and useful Improvements in Combined Window Fasteners and Locks, of which the following is a description, reference being had to the accompanying drawings, which are made a part of this specification.

10 My invention relates to that class of inventions commonly known as "sash-fasteners" or "sash-locks," which are applied to the meeting-rails of window-sashes for the purpose of fastening the two rails together when closed, 15 in order to prevent the windows from being opened, as well as to prevent rattling of the sashes and the undue admission of air between the sashes. In all such window-sash fasteners made prior to my invention the connection 20 between the two sashes when the rails meet is either not made automatically, or, if made automatically, does not draw the two sashes together, and in all such devices the fastening is easily unfastened by any one on the inside 25 of the window, or by any one breaking the glass and reaching his hand through.

The object of my invention is to provide a sash-fastener, one part of which is attached to each of the meeting-rails of the sashes, which 30 shall be automatic in its action to connect the two sashes and to draw the two meeting-rails together, which shall be simple in construction and compact in form, and shall afford a greater security as a lock (not a mere catch. 35 or fastener) than any made prior to my invention.

To this end the invention consists, broadly, in the combination, with a window-sash fastener, preferably automatic in its action, to be 40 applied to the meeting-rails of said sashes, of a key-lock integral with said fastener, whereby the said fastener may be locked or unlocked only with a key; and also in the novel construction of the automatic fastener, which consists, preferably, of two spring-jaws pivotally 45 connected with the upper sash, and which are provided with shoulders, below which is an opening adapted to receive and retain the bolt which is appropriately connected with the 50 lower sash, and also in the various sub-combi-

nations to be hereinafter more fully described, and definitely pointed out in the claims.

The principle of the invention thus consists in combining a key-lock with a sash-fastener, so that when the sashes are fastened it can be 55 locked and unlocked only with a key; and the best mode in which I have contemplated carrying this principle into effect is in the form of device herein shown, although any other mechanical device accomplishing substantially 60 the same intended result by the combination of a window-sash fastener with a key-lock will fall within the principle of my invention, and is intended to be covered by my broad claims.

In the drawings, Figure 1 is a front elevation of the device with the two parts thereof locked together. Fig. 2 is a front view, Fig. 3 a side view, and Fig. 4 a back view, of the automatic spring-jaws and their connections. 70 Fig. 5 is a side view of the bolt and its connections. Figs. 6 and 7 are two vertical sections on the line $x-x$ in Fig. 5. Fig. 8 is a top view of the spring-jaws and bottom plate, with said jaws spread apart. Fig. 9 is a bottom 75 view of the bolt and its connections, with the bottom plate of the housing swung around on its pivot d . Fig. 10 is a detached view of the bolt-rod. Fig. 11 is a side view, and Fig. 12 an end view, of the bolt-socket or key-piece. 80 Fig. 13 is a view of the key used with this form of locking device. Fig. 14 is a detached view of the sliding plate hereinafter described. Fig. 15 is a front elevation of the spring-jaws 85 provided with a brace for holding said jaws open.

A A represent two jaws, which are pivoted at a^2 a^2 to the base-plate B. The adjacent faces of these jaws are at their upper edges sufficiently far apart to permit the introduction 90 of the bolt C, and the said faces are then preferably beveled or curved toward each other for about half their height. They are then abruptly cut away, as shown, thereby forming the shoulders a a , below which the 95 space between said faces is sufficient to permit the bolt to rest while the jaws are in the position shown in Figs. 1, 2, and 4. Connected with said jaws are springs which exert a constant pressure to hold the jaws in the position 100

shown in said figures. The preferable form of said spring and the manner in which it is connected are shown in Fig. 3. It consists of a small coiled spring, *b*, inserted beneath the outer edge of each jaw, one end resting in a socket, *a*³, in said jaws, and thrusts against the bottom plate, *B*, and said jaw to hold it in said position. The backs of the jaws *A A* are preferably beveled, as shown in Fig. 3, for the purpose hereinafter to be explained.

The base *B* consists, preferably, of a flat plate turned up on each side, the screws for fastening it to the window passing through the bottom part and the pivots *a' a'* through the turned-up sides.

The part of the device above described is designed to be fastened to the lower rail of the upper sash. The remaining parts are designed to be fastened to the upper rail of the lower sash.

C represents the bolt, which is fastened at one end to said lower sash, preferably through the instrumentality of the casing or housing *D*, within which said end is shown to be secured. The upper face of the bolt *C* should preferably be horizontal, and should meet the sides at an angle not much greater than a right angle. The bolt, as shown in the drawings, is square.

*The spring-jaws *A A**, heretofore described, and attached to the upper sash, together with the bolt properly secured to the lower sash, make in themselves an automatic window-fastener which prevents the window from being opened from the outside.

The lock part of my device, which is combined with and made integral with said latching device, is as follows: To the free end of the bolt *C* there is fixed a flanged disk, *c'*, the flange or rim of which (marked *c*) has cut into it the slots *c' c'*. Upon the backs of the spring-jaws *A A* are fixed the projecting pins *a' a'*. The slots *c' c'* and the pins *a' a'* are so arranged that when the bolt passes between the jaws *A A* and the said jaws close, when the bolt has reached the enlarged opening between them, the pins *a' a'* pass through said slots when in their normal position as shown in Fig. 5, and lie within the circumference of the flange *c*. If the disk be turned so that the pins *a' a'* cannot pass through said slots, it is evident that the jaws cannot be opened, and the parts will be securely locked together until the slots in the disk are returned to their former position.

The preferable construction for accomplishing the above result is illustrated fully in Figs. 9 to 14, inclusive. That part of the bolt outside the housing *D* is preferably square. Just back of the square portion and within the housing is a cylindrical part, *E*, and back of that is an angular part, *e*, shown square in the drawings, and somewhat larger in diameter than the part *E*, and back of that is another angular part, *e'*, smaller than part *e*. The front and back walls of the casing *D* are per-

forated, the former to admit the bolt, and the latter to receive the bolt-socket or key-piece *G*. This key-piece is short and cylindrical, and has an annular flange, *g*, upon its inner end, into which end is sunk a socket, *g'*, which receives and fits over the angular end *e* of the bolt. Two grooves, *e*², are cut into the bolt, beginning at the end *e* and running some distance into the cylindrical part *E*, and two corresponding grooves, *g*², are cut in the socket *G* from within, which grooves join together and continue through said piece, forming the slot or key-hole *g'*, as shown in Fig. 1.

A plate, *J*, (shown in detail in Fig. 14,) consists, preferably, of a plate bent up to form the sides *j' j'*, which act as guides, and has an orifice, *j*, which practically fits over the angular part *e* of the bolt *C*. A coiled spring, *L*, surrounds said bolt and thrusts against said plate and the front wall of the housing *D*, and thus exerts a constant pressure to hold the plate *J* in the position shown in Fig. 9, when it fits over the angular part *e* of the bolt, and prevents said bolt from turning.

The parts above described are put together as follows: The key-piece *G* is first inserted from the inside of the casing *D*, the flange *g* preventing the same from passing through the wall thereof. The plate *J* and spring *L* are then placed in position, as shown, and the bolt *C* is inserted, passing through the spring and plate, and resting its end in the socket *g'* in the key-piece *G*. A pin, *l*, passes through the bolt within the housing *D* and holds the parts in position.

The operation of the device may be thus explained: As the two meeting-rails of the window-sashes come together the bolt *C* enters between the jaws *A A*, which open to permit it to pass, and then automatically close when it has passed below the shoulders *a a*, which shoulders prevent any upward movement, and the pins *a' a'* pass through the slots *c' c'* and rest within the disk-flange *c*. The front edge of the flange *c* at the same time bears against the beveled backs of the jaws *A A*, thereby drawing the two sashes tightly together. A key, *H*, of the form shown in Fig. 13, for the form of lock herein illustrated, is inserted into the key-hole *g'*. The arms *h h* enter the slots *g' e'* in key-piece *G* and bolt *C*, respectively. The ends of the key strike the plate *J* and press it forward against the spring *L* until said plate is free of the angular portion *e* of the bolt. The key is then given a quarter-turn, and when the key is then withdrawn the plate *J* again engages with the part *e* and prevents further turning of the bolt. As the bolt was turned it carried with it the flanged disk *c'*, and the slots *c' c'* took the position shown in Fig. 1. The pins *a' a'*, it is evident, can no longer pass through said slots, and the jaws cannot be opened. The bolt is thus securely held until said slots are returned to their former position.

The lock herein described is a modification

of a new form of lock to be made the subject of a separate application for a patent to be made before the issuance of the patent on this application.

5 Fig. 15 represents the spring-jaws, provided with a brace designed to hold said jaws apart and permit the use of both hands to open the window. The brace N is pivoted in a groove in one of the jaws, and normally lies in the 10 position shown in the full lines; but when it is desired to hold the jaws open it is turned forward and the jaws separated. The brace then falls between them and holds them in the position shown by the dotted lines until a 15 slight blow from the bolt as it passes upward releases them and returns the brace to its former position, as shown.

As security is one of the principal objects of my invention, it is desirable to have the 20 parts attached to the window-sashes in such a manner that either part cannot be removed while the fastening is locked. This I accomplish with the jaw part by providing a screw-hole in the bottom plate, directly beneath the 25 opening between the two jaws, and so pivoting the jaws that when open, as shown in Fig. 8, a screw can be inserted and fastened to the sash. It is evident that when the bolt is between the jaws said screw is inaccessible. The 30 same result is accomplished with the other part by pivoting the housing D by means of the pivot d to a bottom plate, K, in which are the screw-holes k k, and through these screw-holes the screws pass which fasten the same 35 to the sash.

M represents a flat spring lying transversely across the plate K. One end of said spring M is secured to the upper side of the plate K, and near one edge thereof, and the spring 40 extends across said plate to the other edge thereof. Upon the upper side of the free end of the spring M a nipple, k², preferably of inverted-V shape, is secured. Into the lower edge of the side of the housing, adjacent to 45 the free end of the spring M, a longitudinal groove, d', is cut, corresponding in shape with the nipple k². When the housing D is closed over the plate K, the spring M forces the nipple k² into the groove d'. Thus the plate K 50 and housing D are held together against any accidental force to displace them.

As it is sometimes necessary to remove the sashes, the pivoting of the housing to the bottom plate serves this additional purpose, 55 that it enables me to swing the bolt around out of the way, and thus facilitates the passing of the sashes.

In order to add strength to the connection between the bolt and the sash, which without 60 the following devices might be severed by the mere breaking of the pivot d, I provide the front face of the housing D and of the plate K with the projections d' k³, respectively, which projections dovetail together, as shown, 65 and serve the double purpose of strengthening the device and forming a stop to limit the motion of said housing and plate.

In the form of device herein shown two spring-jaws are used; but the same result could be accomplished by the use of only one jaw, 70 the parts otherwise being arranged in substantially the same manner as herein shown and described; but I regard the use of only one jaw as a mere inferior equivalent of the invention herein described and claimed. 75

Having thus described my invention, what I claim as new, and desire to secure by Letters Patent, is—

1. The combination of a pivoted spring jaw or jaws secured to the upper sash, a bolt secured to the lower sash and automatically engaging with said jaws to hold the sashes together, and a lock to prevent said bolt and jaws from being separated without the use of a key, for the purpose set forth. 85

2. In a sash fastener and lock, the combination of a pivoted spring jaw or jaws with a revolving bolt adapted to engage with said jaw or jaws, substantially as and for the purpose set forth. 90

3. In a combined window fastener and lock, the combination of a pivoted spring jaw or jaws having pins projecting from their rear faces, with a revolving bolt having a device on the free end thereof adapted to engage with 95 said pins by the partial revolution of said bolt, substantially as and for the purpose set forth.

4. In a combined window fastener and lock, the combination of a pivoted spring jaw or 100 jaws, and a revolving bolt adapted to engage with said jaws, with means, substantially as described, for retaining said bolt at various points in its revolution, for the purpose set forth. 105

5. In a combined sash fastener and lock, the combination of the housing D, having the dovetail projection d², with the bottom plate, K, pivoted thereto, and having the dovetail projection k³, substantially as and for the purpose specified. 110

6. In a fastening for the meeting-rails of window-sashes, the combination of pivoted spring-jaws provided with shoulders on their adjacent faces, and cut away below said shoulders, leaving an opening between said jaws, said jaws having their backs beveled, with a bolt adapted to be retained in said opening, and a flange on said bolt for engaging with said beveled backs, substantially as and for 120 the purpose specified. 115

7. The combination of two pivoted spring-jaws having shoulders on their adjacent faces, and two pins attached, respectively, to the backs of said jaws, with a bolt having a flanged 125 disk attached thereto, and two slots cut in said flange, substantially as and for the purpose set forth.

8. In a window-sash fastener, a bolt having on one end a flanged disk with slots in said flange, and having the other end secured in a proper housing, the part within the housing consisting of a cylindrical part, an angular part of larger area in section, and another 130

angular part smaller than the first named and provided with longitudinal grooves combined with the housing, and a sliding plate provided with an angular orifice and a coiled spring, and a bolt-socket having slots which correspond with the slots in the bolt, substantially as and for the purpose set forth.

9. The combination of the housing D, hav-

ing the groove d' , with the plate K, pivoted to said housing, and a spring having a nipple on its free end attached to said plate, for the purpose specified.

FRANCIS F. BROWNE.
